UNITED STATES PATENT OFFICE.

GEORGE F. BRINKERHOFF, OF CUYAHOGA FALLS, OHIO.

PENHOLDER.

1,073,208.

Specification of Letters Patent. Patented Sept. 16, 1913.

Application filed November 9, 1912. Serial No. 730,470.

To all whom it may concern:

Be it known that I, GEORGE F. BRINKERHOFF, a citizen of the United States, residing at Cuyahoga Falls, in the county of 5 Summit and State of Ohio, have invented a new and useful Penholder; and I do hereby declare the following to be a full, clear, and exact description of the invention, such as will enable others skilled in the art to 10 which it appertains to make and use the same.

This invention relates to a new and useful pen-holder.

As one of the objects of the invention, it 15 is the aim to construct the pen point clamping tube in one piece, which is adapted to hold the pen point between the tube and the stick.

Another object of the invention is to provide 20 a reversible clamping tube.

Further, it is an object of the invention to provide a device or clamping tube for holding pens of varying thicknesses.

Another object of the invention is to provide 25 slots at the end of said clamping tube, said slots are of different lengths, and arranged in staggered relations.

As a further object of the invention is the provision of spring arms at both ends 30 of the clamping tube, the spring arms at one end being at right angles or in staggered relation with those of the opposite end.

Another object of the invention, is the provision 35 of a stick having a reduced portion, at one part of which reduced portion, the diameter thereof is increased, whereby the spring arms of either end of the clamping tube are spread apart, or may frictionally engage the portion of increased diameter, to hold the tube in place.

Further, another object, is the provision 40 of an annular shoulder at one end of said reduced portion, in order to limit the tube, when being slipped or telescoped on the stick.

A further object of the invention is the provision 45 of another shoulder upon said stick, to limit the pen point, when being inserted between the tube and the stick.

A further object of the invention is the provision 50 of an inexpensive, durable, simple, and desirable practical pen-holder, and one which can be easily cleaned, and the parts thereof disassembled readily.

In the drawings there are disclosed cer-

tain features of construction, but in practical fields these features may necessitate alterations, to which the patentee is entitled, provided the alterations fall within the scope of what is claimed.

The invention comprises further features and combination of parts, as hereinafter set forth, shown in the drawings and claimed.

In the drawings: Figure 1 is a view in perspective, showing the improved pen holder constructed in accordance with the invention. Fig. 2 is a sectional view on line 2—2 of part of Fig. 1. Fig. 3 is a detail view of the clamping tube.

Referring more particularly to the drawings 1 designates the pen-holder stick, which tapers, as shown, at one end, while the other end is provided with a reduced portion 2, and a shoulder 3 adjoining one end of the reduced portion. This reduced portion at one end, from substantially *a* to *b*, is of a larger diameter in cross section, than the part between *a* and the end of the holder. This part between *a* and *b* is constructed so that the spring arms 5 (which are provided owing to the provision of the slots 6) may engage therewith frictionally, in order to hold the clamping tube against displacement. When the spring arms 5 engage said enlarged part of said reduced portion, they are spread apart slightly, as disclosed in Fig. 2 clearly. A slight distance beyond that portion designated by the letter *a*, the reduced portion is provided with an annular shoulder 7, and from this shoulder 7 the reduced portion tapers slightly as shown, so that a pen point 8 may easily enter between the tapered end of said reduced portion and the arms 9, yet frictionally enough, as to hold the point securely in position. These arms 9 are provided, owing to the construction of the slots 10.

The clamping tube is designed to be constructed of any suitable spring metal, in order to lend resiliency or yieldability to the arms 5 and 9. The arms of either end of the tube are designed for the purpose of holding either the tube or the pen point in place. In other words, the tube is reversible, and in that case pen points, varying in length as well as in thickness may be clamped firmly in place. For example, if the tube is adjusted, so that the arms 5 are used for clamping the pen point, the point cannot be inserted very far in the holder, because of the shortness of said arms, and

owing to their shortness the resiliency or yieldability is greatly lessened. In other words, the nearer the pen point is inserted to the base of said spring arms 5, the less 5 the said arms will yield at their base portions. The spring arms 9 are designed for holding varying lengths of pen points, preferably the greater part of the longer pen points, while the arms 5 hold the shorter 10 points. The arms of either end of the tube are long enough to engage the part between *a* and *b* of the holder, to hold the tube in place, or are long enough to hold a pen-point against the lower end of the holder. 15 The object for making the slots and the arms at right angles to one another, or in staggered relations, is to lessen the chances of weakening the clamping tube, which would occur if the slots and the arms alined with 20 one another.

From the foregoing it is to be ascertained that there has been devised a novel, simple, efficient and inexpensive and desirable practical pen-holder, and one which may be dis- 25 assembled readily for cleaning the same.

The invention having been set forth, what is claimed as new and useful is:—

1. In combination, a stick having a reduced portion, a part of which at one end 30 is of one diameter and terminating in a shoulder, while another part is of a smaller diameter at the other end, said smaller portion terminating in a shoulder, a clamping tube telescoping said reduced portion and 35 provided with spring arms at both ends, the spring arms of one end adapted to frictionally engage the larger portion, while the spring arms of the other end are adapted to clamp a pen point to the smaller part of the 40 reduced portion.

2. In combination, a stick having a reduced portion, a part of which at one end is of one diameter and terminating in a shoulder, while another part is of a smaller diameter at the other end, said smaller portion 45 terminating in a shoulder, a clamping tube telescoping said reduced portion and provided with spring arms at both ends, the spring arms of one end adapted to frictionally engage the larger portion, while the spring arms of the other end are adapted to clamp a pen point to the smaller part of the reduced portion, the first shoulder adapted 50 to limit the clamping tube, while the second shoulder limits the pen point.

3. In combination, a stick having a re-

duced portion, a part of which at one end is of one diameter and terminating in a shoulder, while another part is of a smaller diameter at the other end, said smaller portion 60 terminating in a shoulder, a clamping reversible tube telescoping said reduced portion and provided with spring arms of different lengths and corresponding slots at both ends, the spring arms at one end being at right angles or in staggered relations to those of the opposite end, the spring arms of one end adapted to frictionally engage the larger portion, while the spring arms of the other end are adapted to clamp 70 a pen point to the smaller part of the reduced portion, the first shoulder adapted to limit the clamping tube, while the second shoulder limits the pen point.

4. In combination, a pen holder stick having a reduced portion, a clamping tube having spring arms at both ends telescoping the reduced portion, said clamping tube being reversible, in order that the arms of either end may be adapted for clamping a pen 80 point, the spring arms of one end being of different lengths to and arranged at right angles to the arms of the opposite end, the arms of either end being long enough to engage the reduced portion to hold the tube 85 in place.

5. In combination, a pen holder stick having a reduced portion, a clamping tube having spring arms at both ends telescoping the reduced portion, said clamping tube being reversible, in order that the arms of either end may be adapted for clamping a pen point, the spring arms of one end being of different lengths to and arranged at right angles to the arms of the opposite end, the 95 arms of either end being long enough to engage the reduced portion to hold the tube in place, the pen holder stick having means to limit the clamping tube in telescoping the same on the reduced portion, while the 100 reduced portion is provided with means to limit a pen point when inserting the same between the spring arms at one end and the reduced portion.

In testimony whereof I have signed my 105 name to this specification in the presence of two subscribing witnesses.

GEORGE F. BRINKERHOFF.
